US0D1071421S

(12) **United States Design Patent** (10) **Patent No.:** **US D1,071,421 S**
(45) **Date of Patent:** **** Apr. 15, 2025**

(54) **FRAME FOR A PRESSURE WASHER**

(71) Applicant: **Karcher North America, Inc.**, Aurora, CO (US)

(72) Inventors: **Marcos Moreno Pastor**, San Nicolas de los Garza (MX); **Michael Meyer**, Schwaikheim (DE); **Ana Sofia Marenó Garza**, Monterrey (MX); **Pedro Emilio Reyna Ramos**, Apodaca (MX)

(73) Assignee: **Karcher North America, Inc.**, Aurora, CO (US)

(**) Term: **15 Years**

(21) Appl. No.: **29/837,657**

(22) Filed: **May 6, 2022**

(51) LOC (15) Cl. **15-05**

(52) U.S. Cl.

USPC **D32/15**

(58) **Field of Classification Search**

(57) **CLAIM**

The ornamental design for a frame for a pressure washer as shown and described.

DESCRIPTION

FIG. 1 is a front perspective view of the frame for a pressure washer;

FIG. 2 is a front elevation view of the frame for a pressure washer of FIG. 1;

FIG. 3 is a rear elevation view of the frame for a pressure washer of FIG. 1;

FIG. 4 is a right elevation view of the frame for a pressure washer of FIG. 1;

FIG. 5 is a left elevation view of the frame for a pressure washer of FIG. 1;

FIG. 6 is a top plan view of the frame for a pressure washer of FIG. 1; and,

FIG. 7 is a bottom plan view of the frame for a pressure washer of FIG. 1.

The dotted lines showing portions of the frame for a pressure washer depict environment and form no part of the claimed design.

1 Claim, 7 Drawing Sheets
